GAS REGULATOR.

APPLICATION FILED FEB. 26, 1913.

1,105,841.

Patented Aug. 4, 1914.

UNITED STATES PATENT OFFICE.

JAMES R. RICKETTS AND HERBERT V. LEAHY, OF LOS ANGELES, CALIFORNIA,
ASSIGNORS TO PERFECTION GAS REGULATOR COMPANY, OF LOS ANGELES,
CALIFORNIA, A CORPORATION OF CALIFORNIA.

GAS-REGULATOR.

1,105,841.

Specification of Letters Patent.

Patented Aug. 4, 1914.

Application filed February 25, 1913. Serial No. 750,696.

To all whom it may concern:

Be it known that we, JAMES R. RICKETTS and HERBERT V. LEAHY, both citizens of the United States, residing at Los Angeles, in 5 the county of Los Angeles and State of California, have invented new and useful Improvements in Gas-Regulators, of which the following is a specification.

This invention relates to an improvement 10 over the gas regulator shown in a former application of James R. Ricketts, filed August 14, 1912, Serial No. 715,050, and the object of the present invention is to secure a more perfect seating of the valve so that when it 15 is seated it will bear uniformly on the seat. In the former application referred to the valve is carried by an oscillating arm, the valve being capable of universal movement with respect to the oscillating arm, but the 20 center of movement of the valve is located at such a distance from the valve facing that the valve facing has a considerable lateral movement in swinging through the necessary arc to effect a proper seat.

25 The main object of the present invention is to provide a construction making it possible to locate the center of movement of the valve head very close to the valve facing so that as the valve moves into proper seating position the degree of arc which it describes in coming into proper position is much less, and the lateral movement of the valve facing with respect to the seat is the minimum.

35 Referring to the drawings: Figure 1 is a transverse vertical sectional view through the gas regulator constructed with the improvement. Fig. 2 is a section on line x^2-x^2 , Fig. 1. Fig. 3 is a plan view of the oscillating arm, regulating arm and parts carried thereby. Fig. 4 is a perspective of the valve presser. Fig. 5 is a perspective of the valve. Fig. 6 is a perspective of the valve supporting spring.

45 1 designates the regulator in general, to which gas is conducted through a gas main pipe 2, and from which gas is discharged through a service pipe 3.

The invention relates to the valve mechanism controlling the passage of gas from 50 pipe 2 to pipe 3.

4 is an oscillating arm pivoted at 5, controlled by mechanism responsive to gas pressure, the particular construction of which is described in the former application. 55

6 is a regulating arm also supported at 5 and maintained in desired relation to the oscillating arm 4 by means of a regulating screw 7.

8 designates a valve presser which is 60 loosely pivoted at 9 to the regulating arm 6 in such a manner that the valve presser 8 is capable of some degree of universal movement with respect to the regulating arm 6. A leaf spring 10 is secured to the oscillating 65 arm 4 and bears against the lower rim of the valve presser 8, causing the latter to bear upwardly on the outer end of regulating arm 6 and thereby hold the screw 7 against oscillating arm 4. The spring 10, as clearly 70 shown in Fig. 6, has a circular opening 11 and projecting therethrough is a hollow valve head 12 which has a flange 13 which retains it on the spring 10; and a valve facing 14 of leather or other desired material 75 fills the cupped portion of the valve head.

The valve presser 8 is recessed and a light coil spring 15 therein is interposed between the valve presser and valve head, serving to yieldingly hold the valve head with its 80 flange 13 against the spring 10 when the valve is open, as shown in Fig. 1. The valve presser 8 is also formed with a downwardly projecting convex boss 16 which is adapted to bear against the upper face of the valve 85 head and act as the abutment to press the valve downward and hold it against its seat. The valve seat comprises a plug 17 with a gas passage 18 and having an annular flange 19 against which the valve facing is adapted 90 to be pressed when the valve is closed. When the inner end of the oscillating arm moves up it tilts the regulating arm 6 correspondingly and the latter moves down the valve presser 8, the spring 10 also descending 95 until the valve facing 14 rests against the flanged valve seat 19, at which time further downward movement of the valve is arrested. At this time contact of the valve with its seat is maintained yieldingly by the 100

light spring 15, there being a slight clearance between the abutment 16 and the valve

head so that the abutment does not contact with the valve head immediately when the latter first touches its seat, which gives the valve head a chance to accommodate itself 5 to the seat, which movement is effected by the light spring 15 without damage to the valve facing. The valve is thus preliminarily placed against its seat properly and a slight further downward movement of the 10 valve presser 8 brings the abutment 16 to bear against the valve head and exerts pressure, forcing the valve facing 14 into tight engagement with the seat. The valve may still further adjust itself during the application of pressure from the boss 16 and the bearing point of the boss 16 is so close to the face of the valve that in such adjustment the valve does not have a tendency to rock laterally to any appreciable extent. The 15 convex surface of the box acts as a fulcrum and presses against the center of the valve so that the valve can find its natural seat.

The purpose of the loose connection of the valve presser 8 with the regulating lever 6 is to enable the regulating lever 6 to be adjusted by screw 7 into various angular positions with respect to oscillating arm 4 without distorting the position of the valve presser 8 with respect to the leaf spring 10. 20 If the valve presser 8 were carried rigidly by the regulating arm 6 when the latter was adjusted, it would swing the lower rim of valve presser 8 out of perfect contact with the spring 10.

We prefer to allow the slight space between the boss 16 and valve head as, if the boss touched the valve head, it would exert such pressure upon the valve at the initial seating of the valve that it would not so 25 readily allow the valve to shift in finding a perfect seat. With the slight clearance, however, the light spring 15 holds the valve so lightly against the seat that the valve can find its seat before pressure is exerted 30 against it by the boss 16.

What we claim is:

1. In a gas regulator, a valve seat, an oscillating arm, a regulating arm adjustable with respect to the oscillating arm, a valve presser carried by the regulating arm, a valve head supported below the valve presser, abutment means between the valve presser and valve head for pressing the valve head against the seat, there being a 35 connection permitting universal movement between the valve presser and regulating arm, and there being another universal movement between the valve head and said abutment.
2. In a gas regulator, an oscillating arm, a regulating arm adjustable with respect to the oscillating arm, a valve presser loosely carried by the regulating arm, a valve head, means yieldingly supporting the valve head,

65 a valve seat against which the head is adapted to be pressed, and abutment means between the valve presser and valve for moving the valve against its seat.

3. In a gas regulator, an oscillating arm, a regulating arm adjustable with respect thereto, a valve presser having a universal connection with the regulating arm, a leaf spring carried by the oscillating arm and bearing against the lower part of the valve presser, a valve seat, a valve head between 70 said seat and valve presser, the valve presser having a convex abutment adapted to bear against the valve head to move the same against said seat, and a coil spring between the valve presser and valve head.

4. In a gas regulator, a movable arm, a regulating arm adjustable with respect to the movable arm, a valve presser loosely carried by the regulating arm and being recessed in its lower part and formed with 85 a convex boss in the recess, a leaf spring secured to the movable arm and bearing against the lower rim of the valve presser and having an opening, a valve head projecting through the opening in said spring 90 and having a flange which rests upon said spring, a coil spring within the recessed portion of the valve presser between the valve presser and valve head, and a valve seat below the valve head.

95 5. In a gas regulator, a movable arm, a regulating arm adjustable with respect thereto, a valve presser carried by the regulating arm, a valve seat, spring means supporting said valve above said seat, spring 100 means between the valve presser and valve head for exerting a pressure against the valve head, tending to move it toward its seat, and abutment means between the valve presser and valve head, there being a slight 105 clearance between the abutment means and valve head when the valve is opened.

6. In a gas regulator, a valve seat, a valve movable to and from said seat, pressure controlled means for operating said valve, 110 means yieldingly holding said valve against said pressure controlled means, said pressure controlled means having an abutment bearing against the back of said valve at a point in line with and close to the seat contacting surface of said valve, there being a universal movement between said abutment and the back of said valve, and there being a universal movement at another point of said pressure controlled means.

115 7. In a gas regulator, a valve seat, a valve movable to and from said seat, pressure controlled means for operating said valve, said valve having a universal movement with respect to said pressure controlled means, said 120 pressure controlled means having an abutment for bearing against said valve at a point close to the seat contacting surface of

said valve, and a light spring holding said valve out of contact with said abutment means when the valve is opened and acting to exert a preliminary pressure against the valve when the valve is closed before the abutment means comes in contact with the valve.

In testimony whereof, we have hereunto

set our hands at Los Angeles, California this 17th day of February, 1913.

JAMES R. RICKETTS.
HERBERT V. LEAHY.
